JOSEPH J. SHOEMAKER, OF CLAWSON, MICHIGAN, ASSIGNOR OF ONE-THIRD TO KENNETH H. QUAIL, OF ROYAL OAK, MICHIGAN

EXERCISING APPARATUS

Application filed July 10, 1929. Serial No. 377,173.

My invention relates to an exercising apparatus for children and an object of my improvements is to provide a compact, strong and cheap apparatus adapted to be adjusted to different requirements and that may be readily constructed from stock that may be procured in the open market.

I secure this object in the device illustrated in the accompanying drawings, in 10 which:

Figure 1 is a side view of an apparatus embodying my invention.

Figure 2 is an elevation looking from the right of Figure 1, a portion being broken 15 away.

Figure 3 is a section on the line III, III, Figure 1, looking in the direction of the arrow.

Figure 4 is a detail plan view showing the 20 right hand end of the base A.

Figure 5 is a detail sectional view on the line V, V, Figure 1.

Figure 6 is a detail view of the seat portion 25 separate from the apparatus.

Figure 7 is a detail view of one of the spring bars.

Figure 8 is a side elevation of a portion of the part 2 of the base.

The base A is made up of a longitudinal 30 girder 2, which may be a plank of the form shown in Figure 1 placed with its breadth in a vertical plane.

3, 3 are cross pieces placed at the ends of the girder 2 and extending equally on both sides 35 of the same. The cross pieces 3 are connected to the member 2 by a short piece of angle iron 23 secured in the corners between the parts to be united by bolts 23a passing through said parts and through the flanges of the angle iron.

4 is a straight bar of spring steel rectangular in cross section and of the proper dimensions for the purpose indicated. 5 is a piece of angle iron having flanges 5a and 5b. The 45 flange 5a lies against one side of the member 2 and is pivoted thereto by a bolt 25 passing through said flange and through a bolt-hole in the part 2. 45 are U-bolts passing over one end of said bar 4 that lies upon a flange 5b and through holes in said flange and serving

with the usual nuts to bind said bar against the upper surface of said flange. 5ab are holes spaced from each other in an arc of a circle from the bolt 25 at the opposite end of the flange 5a.

55 2a indicates a series of holes, three in this instance, through the member 2 in the arc of a circle from the bolt 25, so that they will register with the holes 5ab as the angle iron 5 is turned about the bolt 25. 52 is a bolt adapted to pass through the holes 5ab and 2a. The bolt 52 may be placed in any pair of registering holes, thus securing six points of angular adjustment for the iron 5 and the bar 4 secured thereon.

6 is a seat portion. This is provided with two arms 6a, 6a extending parallel to each other with a convenient space therebetween. The seat portion 6 is secured to the outer end of the bar 4 by a strap 46 and bolts 46a, with 70 the arms 6a extending along the bar 4. 7 is an ornamental portion, which may represent a horse's head, placed between the arms 6a and secured thereto by bolts 67. This constitutes a hobby-horse construction.

75 8 is a stirrup piece having indentations 8a, 8a, to receive the foot of the rider, in its upper surface. 48 is a strap by which the stirrup 8 is secured to the bar 4, by means of bolts 48a.

A bar 4 with its attached parts is secured, as above described, to each side of the member 2 upon opposite sides of the center of the part 2 and extending at an angle upward and toward the further end of said member.

80 Children may occupy the seats 6 and will thus face each other and by a movement of the body may secure an oscillating movement, due to the resilience of the bar 4.

The bar 4 may be adjusted in position to suit 90 the weight that it is required to hold by angular adjustment around the bolt 25 and secured in the required position by the bolt 52, as above described.

Should it be desired to strengthen one 95 of the bars 4 to sustain an unusual load a short piece of similar steel 9 may be placed under the bar 4, as shown at the right of Figure 1, and secured in position by the U-bolts 45, or such a piece of steel may be placed above 100

the bar 4, as shown at 9a in Figure 1, and an adjustable collar 10 may encircle the bar and said piece to bind them together. The collar may be adjusted longitudinally of the bar and 5 fixed in any desired position by a set screw 10a to adjust and regulate the resistance to bending.

The base A may be made of two inch plank and all the metal parts are conventional stock 10 that may be purchased in the open market and simply cut to the right length and drilled to receive the bolts.

What I claim is:

1. In an apparatus of the kind described, a 15 base piece having two vertical sides, bar springs secured at their ends in inclined positions to opposite sides of said base piece midway between the ends of said base piece and extending in opposite directions and a 20 hobby-horse construction on each spring.
2. In an apparatus of the kind described, the combination of a base piece having a vertical side, a piece of angle iron having one flange engaging against said side and secured 25 to said base piece and the other extending in a plane at right angles to the same, a bar spring secured to the last named flange, said piece of angle iron being pivotally secured to said base piece by a bolt passing through the 30 first named flange and said base piece and a hobby-horse construction on said spring.
3. In an apparatus of the kind described, the combination of a base piece having a vertical side, a piece of angle iron having one 35 flange engaging against said side and the other extending in a plane at right angles to the same, a bar spring secured to the last named flange, said piece of angle iron being pivotally secured to said base piece by a bolt 40 passing through the first named flange and said base piece, said first named flange being provided with a hole passing therethrough remote from said pivotal bolt, a plurality of holes in said base piece adapted to register 45 with said hole through the flange as the same is turned about said bolt and a bolt adapted to engage in said holes, for the purpose described and a hobby-horse construction on said spring.
4. In an apparatus of the kind described, the combination of a base piece consisting of a 50 straight piece of timber with its sides in a vertical plane, cross pieces at the ends of said timber, said cross pieces being secured to said timber by pieces of angle iron and bar springs secured at their ends in an inclined position at opposite sides of said timber and midway the ends of said timber and extending in opposite directions.
5. In an apparatus of the kind described, the combination of a base piece having a vertical side, a piece of angle iron having one flange engaging against said side and secured 55 to said base piece and the other extending in a plane at right angles to the same, a bar 60

spring secured to the last named flange, said piece of angle iron being pivotally secured to said base piece by a bolt passing through the first named flange and said base piece, said first named flange being provided with a plurality of holes passing therethrough remote from said pivotal bolt, a plurality of holes in said base piece adapted to register with said holes through the flange as the same is turned about said bolt and a bolt 70 adapted to engage in said holes, for the purpose described and a hobby-horse construction on said spring.

6. In an apparatus of the kind described, the combination of a base piece consisting of a straight piece of timber with its sides in a vertical plane, cross pieces supporting said timber, said cross pieces being secured to said timber by pieces of angle-iron, and bar springs each of the said springs being secured at its end to one flange of a piece of angle-iron the other flanges of the pieces of angle-iron secured to the ends of said bars being secured to opposite vertical sides of said timber, said springs extending in opposite inclined directions, and a hobby-horse construction upon each of said springs.

7. In an apparatus of the kind described, the combination of a base piece consisting of a straight piece of timber with its sides in a vertical plane, bar springs each of said springs being secured at its end to one flange of a piece of angle-iron the other flanges of the pieces of angle-iron being secured to opposite vertical sides of said timber midway 90 between the ends of said timber, said springs extending in opposite inclined directions, and a hobby-horse construction upon each of said springs.

8. In an apparatus of the kind described, the combination of a base piece consisting of a straight piece of timber with its sides in a vertical plane, bar springs, each of said springs being secured at its end to one flange of a piece of angle-iron the other flanges of the pieces of angle-iron secured to the ends of said bars being pivotally secured to opposite vertical sides of said timber midway 100 between the ends of said timber said springs extending in opposite inclined directions means for fixing said pivotally secured angle-irons at a predetermined angle and a hobby-horse construction upon each of said springs.

In testimony whereof, I sign this specification.

JOSEPH J. SHOEMAKER.
